FIG. 1 is a perspective view taken from the left front side of a door embodying my new design;

FIG. 2 is an enlarged rear elevation foreshortened in several places, of the embodiment shown in FIG. 1;

FIG. 3 is an enlarged side elevation of the embodiment shown in FIG. 1 taken as indicated by the lines and arrows 3—3 in FIG. 2, foreshortened in several places;

FIG. 4 is a greatly enlarged partial top view taken as indicated by the lines and arrows 4—4 in FIG. 2;

FIG. 5 is a greatly enlarged section taken as indicated by the lines and arrows 5—5 in FIG. 2;

FIG. 6 is a perspective view taken from the left front side of another door;

FIG. 7 is an enlarged rear elevation foreshortened in several places of the embodiment shown in FIG. 6;

FIG. 8 is an enlarged right side elevation of the embodiment shown in FIG. 6, taken as indicated by the lines and arrows 8—8 in FIG. 7, foreshortened in several places;

FIG. 9 is a greatly enlarged partial top view taken as indicated by the lines and arrows 9—9 in FIG. 7;

FIG. 10 is a perspective view taken from the left front side of another door;

FIG. 11 is an enlarged rear elevation foreshortened in several places of the embodiment shown in FIG. 10;

FIG. 12 is an enlarged right side elevation foreshortened in several places of the embodiment shown in FIG. 10, taken as indicated by the lines and arrows 12—12 in FIG. 11;

FIG. 13 is a greatly enlarged partial top view taken as indicated by the lines and arrows 13—13 in FIG. 11;

FIG. 14 is a perspective view taken from the left front side of another door;

FIG. 15 is a perspective view taken from the left front side of another door; and

FIG. 16 is a perspective view taken from the left front side of another door.

This is a division of design application Ser. No. D. 23,254, filed June 1, 1970.

I claim:

The ornamental design for a door, as shown and described.
